UNITED STATES PATENT OFFICE.

FRED E. RANNEY, OF GREENVILLE, MICHIGAN.

DESIGN FOR A HINGE.

SPECIFICATION forming part of Design No. 31,307, dated August 1, 1899.

Application filed June 22, 1899. Serial No. 721,487. Term of patent 3½ years.

To all whom it may concern:

Be it known that I, FRED E. RANNEY, a citizen of the United States, residing at Greenville, in the county of Montcalm and State of Michigan, have invented and produced a new and original Design for a Hinge, of which the following is a specification.

The invention relates to a new and original design for a hinge; and it has for its object to provide a design of this character that shall be both useful and ornamental.

The leading feature of the design resides in one leaf or member of the hinge being elongated and provided with an inner solid portion with longitudinal ribs and having an outer open-work portion provided at the extremity with a cluster of leaf-like figures, connected with the inner solid portion by ornamental scrolls, and the other leaf or member being provided with irregularly-scalloped edges and having leaf-like figures at the center and one end and an ornamental scroll at the other end.

In the drawings, Figure 1 is a plan view of a hinge, showing my new and original design. Fig. 2 is an edge view.

Referring to the drawings, 1 designates a hinge having ornamental leaves or members 2 and 3, the leaf or member 2 being elongated and composed of an open-work outer portion 4 and a solid inner portion 5, provided with parallel ornamental longitudinal ribs 6, forming intervening grooves or depressions and merging at their outer ends into ornamental scrolls 7. The ornamental scrolls 7 are connected at their inner portions with the side walls or portions of the central longitudinal

ribs 6 by raised ridges 8, and the outer portions of the scrolls are connected with a cluster of leaf-like figures 9. The ridges 7 and 40 the leaf-like figures 9 are raised to throw them in relief.

The leaf or member 3, which has an irregularly-scalloped edge, is provided at one end with an ornamental scroll 10, and it has leaf-like figures 11 and 12, located, respectively, at its other end and at its center. These leaf-like figures 11 and 12 and the scroll 10 are thrown into relief by the adjacent depressed portions.

The leaves or members of the hinge are provided at their adjacent corners with overlapping ears, connected by a pintle, on which is arranged a spring 13, disposed transversely of the hinge and located in an opening or 55 space between the inner ends of the leaves or members. The spring presents a continuous unbroken coil extending from one side of the hinge to the other, and the terminals of the spring are extended longitudinally of the 60 hinge and are arranged at opposite sides thereof, being located on the outer faces of the adjacent portions of the leaves or sections.

What I claim is—

The design for a hinge, herein shown and 65 described.

In testimony that I claim the foregoing as my own I have hereto affixed my signature in the presence of two witnesses.

FRED E. RANNEY.
